UNITED STATES PATENT OFFICE.

EMANUEL AUFIERO, OF BROOKLYN, NEW YORK.

WARNING SIGNAL.

Application filed March 21, 1921. Serial No. 453,880.

This invention relates to warning signals of the type known as electric horns. Such horns are almost universally used in automobiles where electric current is available for 5 operating the horn, and comprise essentially an acoustic diaphragm and a vibrating mechanism operated by the rotation of a miniature electric motor.

In a certain type of horn now most generally used, the motor is enclosed in a casing adjacent the diaphragm with the motor shaft perpendicular to the diaphragm and provided with a notched wheel or actuator directly engaging the center contact or anvil 10 of the diaphragm. In such horns it is highly desirable that the degree of engagement or overlapping of the notches of the actuator, and the point of the anvil, be accurately maintained, and to this end the motor shaft must be held against lost motion in a axial 15 direction both toward and away from the diaphragm, and must also be adjustable toward and away from the diaphragm to compensate for wear of the bearings and the contacting faces of the actuator and anvil.

Various methods of mounting the motor shaft for this purpose have been proposed and some have been more or less successful in actual practice, but at this date the motor shaft mounting in all horn constructions of 20 this type with which I am familiar is one of the chief sources of trouble, and it is the object of the present invention to provide a motor shaft mounting for horns of this type which will be of simple, rugged construction, 25 easily adjusted and not liable to get out of order, and which will maintain the shaft accurately in adjusted position without lost motion.

A further object is that of providing a signalling device, the parts of which will be 30 individually simple and rugged in construction and capable of being readily assembled to provide an article operating over long 35 periods of time with freedom from mechanical difficulty, and which may be produced at relatively nominal cost.

In the accompanying drawings I have illustrated a preferred embodiment of my improved horn construction, and in said drawings,

Figure 1 is a longitudinal section through the horn and motor casing; and

Fig. 2 is a detail view of the motor frame 55 looking from the right of Fig. 1.

Referring to the drawings, 3 indicates the

diaphragm of the horn supported to the rear of the amplifier 4 by means of the diaphragm housing 5. The diaphragm is vibrated by means of an actuator 7 supported on the end 60 of the motor shaft 6 in position to engage the anvil 8 at the center of the diaphragm. The motor is of usual construction so far as its field coils, armature, brushes, etc., are concerned, and as shown is supported in a rectangular sheet metal frame 9, the front and rear pieces of which are punched to provide bearings for the motor shaft 6. The front end of the motor shaft carrying the actuator projects into the housing 5 in the manner shown, 70 and the rear end of the shaft 6 projects through the bearing in the rear bar of the frame in position to be engaged by the devices for effecting the adjustment of the shaft which forms the subject-matter of this application.

The projecting end of the shaft 6 is conical to fit a bearing cup 16 fixed to a sheet metal arm or strip 10 adjustably supported on the rear bar of the rectangular frame 9. As 80 shown, the strap 10 is L shaped and has its outer end, which is bent to lie parallel with the motor shaft, projected through a hole in the rear bar of the frame 9. Between the shaft and the end 13 the strap is supported 85 on an adjusting screw 11 threaded in the motor frame and provided with a spring lying between the strap and the motor frame with sufficient strength to hold the strap 90 against the head of the screw and in substantial parallelism with the motor frame.

The other end of the strap projects somewhat beyond the bearing cup 16 and is provided with a tapped opening in which is threaded a screw 14 having at its inner end 95 a disk or flat head 17, the edge of which lies in a groove 15 formed in the motor shaft near the end. The screw 14 is also provided with a lock nut 18 whereby it may be locked in adjusted position. When adjusting the 100 horn the screw 14 will first be adjusted to seat the end of the shaft against the bearing cup 16 in a manner to take up all lost motion without undesirable friction between the shaft and the bearing cup. Then the 105 screw 11 will be screwed in or out, as the case may be, to give the desired overlapping of the teeth of the actuator 7 and the anvil 8 for the proper tone of the horn.

By this arrangement the working thrust of 110 the shaft 6 is taken up by the cone bearing instead of by the contacting faces of the

groove 15 and the head 17, the groove being for the purpose appreciably wider than the thickness of the head. As the bearing wears the screw 14 may be adjusted to draw the 5 shaft back against the bearing and the screw 11 screwed up to shift the entire motor shaft and armature toward the diaphragm to compensate for the wear both of the bearing and the contacting faces of the actuator and 10 the anvil.

As the conical thrust bearing is directly in line with the working thrust transmitted through the bearing at the front end of the motor shaft, the thrust bearing wears evenly 15 and slowly, and the horn will remain in operative adjustment without attention for long periods. Also, the thrust of the cone bearing on the end of the shaft prevents lateral play of the shaft in the bearings in the frame 9, 20 which also prolongs the life of the horn. The mechanism is of simple design and is supported entirely at the rear of the motor frame where it is easily accessible upon removing the motor casing.

25 My improved shaft mounting has been shown and described in considerable detail in its preferred form, but it is to be understood that the invention is not limited to such details, except in so far as recited in the append- 30 ed claims.

I claim:

1. In a device of the class described, a frame, a shaft supported in said frame, and means for adjusting said shaft relatively to 35 said frame comprising a member supported on the frame and adjustable in the axial direction of said shaft, a screw threaded in said frame for effecting the adjustment of said member, a thrust bearing carried by said 40 member and engaging the end of said shaft, said shaft having a groove adjacent said bearing, and a second adjusting screw threaded in said member with its head engaging said groove for maintaining said shaft in engagement with said thrust bearing.

2. In a device of the class described a wall, 50 a shaft having an end portion journaled in said wall, and having an annular groove in its end beyond said wall, an angular or cross bar having one end engaged with said wall and its opposite end bearing upon the end of 55 said shaft, a headed screw adjustably engaged with said wall and extending through an opening in said cross bar at one side of said shaft, spring means mounted on said screw member, and holding said cross bar in engagement with the head of said screw, and a member adjustably carried by said bar and extending into said groove to retain the 60 shaft in engagement with said bar.

3. A device of the class described, comprising a wall, a shaft having an end portion journaled in said wall, and having an annular groove near its end beyond said wall, a cross bar having one end engaged with said wall 65 and its opposite end bearing upon the end of said shaft, a member adjustably engaged with said wall and extended through said cross bar and provided with stop means engaging said cross bar, a spring mounted on 70 said member and interposed between the wall and the cross bar for holding said cross bar in engagement with said stop means and a member adjustably carried by said bar and extending into said groove to retain the shaft 75 in engagement with said bar.

4. A signal, including a diaphragm, means for mounting the same, a driving shaft, a diaphragm-actuating mechanism, one of the elements thereof being secured to said shaft 80 and another to said diaphragm, a frame through which said shaft extends, an angular bar having one of its ends in slidable contact with said frame, said bar engaging the shaft end to provide a bearing therefor, and 85 means carried by said bar and engaging said shaft to retain the end of the latter into contact with the bar.

5. A signal, including a diaphragm, means for mounting the same, a driving shaft, a 90 diaphragm-actuating mechanism, one of the elements thereof being secured to said shaft and another to said diaphragm, a frame through which said shaft extends, a bar providing a bearing for said shaft, a member adjustably connecting the bar and frame to vary the degree of cooperation of the parts of the diaphragm-actuating mechanism, and means adjustably carried by said bar and connected with the shaft to retain the latter 100 in bearing engagement with said bar.

6. A signal, including a diaphragm, means for mounting the same, a driving shaft, a diaphragm-actuating mechanism, one of the elements thereof being secured to said shaft 105 and another to said diaphragm, a frame through which said shaft extends, a bar providing a bearing for said shaft, a member adjustably connecting the bar and frame to vary the degree of cooperation of the parts 110 of the diaphragm-actuating mechanism, said shaft being formed with an annular groove adjacent its end, and a headed member adjustably carried by said bar and having its head extending into the groove of said shaft 115 to retain said shaft in proper bearing engagement with said bar.

In testimony whereof I affix my signature.

EMANUEL AUFIERO.
